UNITED STATES PATENT OFFICE.

HENRY J. FAUBEL AND WILLIAM ROACH, OF ALLIANCE, OHIO.

RAILWAY-TIE AND FASTENING THEREFOR.

1,145,298.

Specification of Letters Patent.

Patented July 6, 1915.

Application filed January 20, 1915. Serial No. 3,348.

To all whom it may concern:

Be it known that we, HENRY J. FAUBEL and WILLIAM ROACH, citizens of the United States, residing at Alliance, in the county of Stark and State of Ohio, have invented new and useful Improvements in Railway-Ties and Fastenings Therefor, of which the following is a specification.

The present invention relates to improvements in means for connecting and supporting the meeting ends of two railway rails, and may be considered in the nature of an improvement upon Patent No. 1,100,550 which was granted us by the United States Patent Office on June 16, 1914.

Other objects and advantages of our construction will appear as the nature thereof is more fully disclosed, reference being had to the accompanying drawing in which there 20 is exemplified a satisfactory reduction to practice of our improvement as it now appears to us, it being understood, however, that the showing in the drawings is merely illustrative and that we are entitled to all 25 such changes in material, construction and arrangement of parts as fall within the scope of our claims.

In the said drawing: Figure 1 is a perspective view illustrating two railway rails 30 connected in accordance with our invention, Fig. 2 is a vertical transverse sectional view approximately on the line $a-a$ of Fig. 4, Fig. 3 is a similar sectional view approximately on the line $b-b$ of Fig. 4, Fig. 4 is 35 a horizontal sectional view approximately on the line $c-c$ of Fig. 2, Fig. 5 is a perspective view of one of the fish plates, and Fig. 6 is a similar view of one of the locking members or keys.

40 In carrying out our invention we employ a metal tie, substantially similar to that disclosed in our aforementioned Patent No. 1,100,550, and as our improvement is adapted to co-act with such a tie, a brief description 45 of the same is deemed necessary. The tie, indicated by the numeral 1, comprises a trough-like structure and is integrally formed, adjacent its opposite ends with blocks 2, the upper faces of the same being 50 parallel with the opposite edges of the side members of the metallic trough-like body, the said blocks being of a width corresponding with the width of the base flanges of the rails for which they provide a support. 55 The outer sides of the body 1 are formed with laterally extending lugs or shelves 3,

the same being arranged longitudinally of the block 2 and the upper faces as well as the sides of the said lugs or brackets being disposed flush with the upper face and sides 60 of the block 2. Each of the lugs or brackets 3 is provided with a transversely arranged substantially rectangular opening 4, while the block 2 is provided with two spaced similar openings 5 and 6 respectively. Integrally formed upon the upper faces of the shelves 3 and at the longitudinal edges thereof and adjacent their ends are vertically projecting lugs 7, the same being preferably rectangular in cross section, and likewise projecting from the side members of the tie or from the block 2 adjacent its connection with the said side members of the tie are similar lugs 8-8.

The rails, indicated by the characters 75 R-R, are of ordinary construction, but the base of each of the rails is provided at its longitudinal edge with pairs of notches 9 which are adapted to receive the pairs of respective lugs 7 and 8, when the said rails 80 are arranged upon the seat provided by the block 2 and the shelves 3. The webs of the rails are provided with the usual bolt openings 10.

The numerals 11 designate the fish plates, 85 both of which being of a similar construction and each of which, of course, adapted to be received within the fishing spaces to the opposite sides of the rails and to contact with both the underfaces of the heads as 90 well as with the base flanges of the said rails. Each of the fish plates is provided, adjacent one of its ends, with a pair of spaced laterally projecting pins 12 and is also provided, adjacent its opposite end, 95 with a pair of spaced orifices 13. The pins 12 of each of the fish plates pass through the pair of openings in each of the rail ends and are likewise received in the orifices 3 of the adjacent plate. Integrally formed upon the 100 outer face of each of the fish plates and at a suitable distance beyond its center is a substantially rectangular member or hook 14, the same being shaped to agree with the contour of the upper face of the base flange 105 of the rail as well as to engage with the outer longitudinal edge of the rail, and each of the said hooks 14 is provided with a lateral extension 15 which projects as a horizontal arm, and one of each of the said arms 110 is adapted to be passed through one of the lateral openings 5 or 6 in the block 2 and to

extend a suitable distance beyond the side of the block. The end of each of the arms 15 is provided with an elongated slot 16, and each of the blocks 2 below its respective openings 5 and 6 is formed with a depression 17, the upper wall of which being horizontally straight and forming a shoulder 18.

The numerals 20 designate the key members which are adapted to be passed through the openings 16 in the arms 15. The head 21 of each of the keys 20 has its underface shaped to snugly engage with the upper wall of the base flange of one of the rails and is of a length sufficient to contact with one of the fish plates. The shank 22 of each of the keys, is, formed upon one of the ends of the head and comprises an inner vertically straight, substantially rectangular, member or arm 23, having a lateral lug 24 formed upon the inner face thereof adjacent the end of the said arm, and a spring member 25, having an outer beveled face disposed opposite the said arm 23. The spring member may be formed by slitting the shank 22 longitudinally, the said slot terminating in a line with the lower face of the head 21, and as the key is constructed of metal, the arm 23 also possesses a certain amount of resiliency. When the key is inserted through the opening 16 the spring member 25 contacting with the outer wall of the opening will be forced toward the arm 23 and the transverse lug 24 will be forced in the pocket 17 and have its upper edge contact with the shoulder 18, so it will be noted that the key not only contacts and provides a support or brace for the co-acting fish plate, but the same contacting with the rail serves as an effective means for preventing the lateral movement of the said rail, and also that the key cannot be accidentally disengaged by vibration incident to the rolling stock passing over the joint, but its lug end must be withdrawn from the pocket 17 before the said key can be separated from the arm, 15.

For the ends of the fish plates we provide clamping members 26, each constructed from a substantially rectangular member 50 comprising each a hook shaped end 27 which is adapted to engage with one of the said fish plates to overlie the base flange of the rail beyond the said fish plate as well as to contact with the longitudinal edge of the said rail. The hooked ends are provided with longitudinally extending arms 28 which are passed in reverse direction through the openings 4 in the respective shelves 3, and the arms 28, adjacent their free ends, are provided with elongated openings 29. These openings are adapted to receive the shanks of spring keys 30, similar to the keys 22, and the shelves are provided with depressions 31 having their upper walls 55 horizontally straight to provide shoulders 32

which engage with the upper edges of the lateral lugs 33 provided upon the inner arms of the keys 30.

From the above description, taken in connection with the drawing, it will be noted that the arms 15 are so arranged upon the respective fish plates that either of the said plates may be inserted through the opening 5 or 6 from either of the sides of the block 2 and that the same will have their pins at 75 all times in proper register with the bolt openings in the webs of the rails and with the orifices of the co-acting plates.

It will be further noted that we have provided a simple and cheap but thoroughly 80 effective means for securing the meeting ends of the rails and for connecting the said rails to the tie. The structure is such that the lateral or downward movement of the rails will be effectively overcome and that 85 the said rails are provided with a comparatively long support which co-acts with the rails to assist in preventing any twisting or lateral movement thereof, but which permits of a certain desired amount of longitudinal movement incident to the expansion and contraction of the rails, and it is now thought that the advantages of the improvement will be apparent and appreciated. 90

Having thus described the invention, what 95 we claim is:

1. In combination, a channeled tie having a rail supporting block thereon and rails resting upon the block, of fish plates upon the opposite sides of the rails, a hooked member upon each of the plates and including a longitudinal arm having a slotted end, the said arms passing in opposite directions through openings in the blocks, and headed key members passing through the respective 105 openings in the arms and contacting with the fish plates.

2. In combination with a channeled tie having a block providing a rail seat, and rails upon the seat, of fish plates upon the 110 opposite sides of the rails, each of said plates being provided with lateral pins which register with the bolt openings in one of the rails and with orifices which register with the bolt openings in the second rail, 115 and the pins of one of the plates adapted to pass through the said openings in the rail and to be received in the orifices of the second fish plate, each of the plates having rail-engaging hooks, and longitudinally extending arms formed therewith, the said arms having their ends provided with openings and passing in opposite directions through openings in the block, and headed key members having spring shanks which 120 are passed through the openings in the respective arms and the heads of the said keys contacting with the respective fish plates.

3. In combination with a tie having a rail receiving block and rails upon the block, of 130

- fish plates within the fishing spaces of the rails at the meeting ends thereof, each of said plates having integral members disposed within the bolt openings of the rails, each of 5 said plates having a hook disposed beyond its center provided with a longitudinally extending arm and having an opening at its end, said arms passing in opposite directions through openings in the blocks, headed 10 key members having spring shanks passed through openings in the arm, said shanks of the keys having transverse lugs which contact with the opposite sides of the block.
4. In combination with a tie having a rail 15 receiving block and rails upon the block, lugs upon the block co-acting with notches in the base flanges of the rails, fish plates upon the opposite sides of the rails, lateral members upon each of the fish plates and passing 20 through the bolt openings in the rails and being received within orifices in the adjacent fish plate, each of said plates having a rail engaging hook disposed away from its center and each of the said hooks being formed 25 with longitudinally extending arms having their ends provided with openings, and the said arms adapted to pass in opposite directions through openings in the block, said block below its opening being recessed to 30 provide an upper shoulder, headed keys passing through the openings in the arms and the heads of the said keys contacting with the rails and with the fish plates, the shanks of said keys being slotted longitudinally and 35 the inner face of each of the keys being provided with a transverse lug which is adapted to be received within the recesses in the block and to engage with the shoulders provided by the said recesses.
- 40 5. A rail connecting means including fish plates having members passing through the openings in the webs of the rails and received within orifices in the respective fish plates, each of said plates having a rail engaging 45 hook formed with a longitudinal arm which extends laterally below the rails, said arm having its end provided with an opening, a key including a headed member passing through the opening in each of the arms and 50 engaging with the rail and contacting with the respective fish plate, and the shanks of the keys being slotted to provide an inner straight member and an outer beveled member, said straight member having a trans- 55 verse lug which is disposed beneath the arm.
6. In combination, a tie having a rail receiving block and shelves extending laterally of the tie and providing continuations of the block, said block and shelves having upturned lugs received within notches in the 60 base flange of the rail, fish plates upon the opposite sides of the rails and having members engaging within the bolt openings of the rails, a hook formed with each of the plates disposed beyond its center and engaging 65 one of the rails, arms having their outer ends provided with openings passing through openings in the block, headed key members passing through openings in the arms and contacting with both the fish plate and base 70 of the rail, said keys including spring shanks comprising an inner straight arm and an outer beveled arm, the said straight arm having a transverse lug, said lug adapted to be received within a recess in the block to contact with the walls thereof, clamp members for the rails and passing through openings in the brackets, said clamps each including a hooked end and a longitudinally extending arm having its end provided with an opening, and key members having rail engaging 75 heads and spring slotted shanks passing through the openings in the arms, and the inner arms of the said key members being provided with transverse lugs received in 80 and contacting the walls of recesses provided in the sides of the said shelves.
7. A fish plate having one of its ends provided with inwardly extending lugs, its opposite end provided with orifices, a rail engaging hook disposed beyond its center, and the said hook being formed with a longitudinally extending arm having an opening therein and a wedge key provided with a lateral rail-engaging head and a split resilient 85 shank for the opening.
8. The herein described construction of wedge keys including a head, a laterally extending spring shank formed from one end of the head, and the inner member of the 90 split shank having a transverse lug, the outer member having its outer face inclined.

In testimony whereof we affix our signatures in presence of two witnesses.
